JESSE BROWN WALKER, OF SAVANNAH, TENNESSEE.

INTERNAL-COMBUSTION ENGINE.

1,122,823.

Specification of Letters Patent. Patented Dec. 29, 1914.

Application filed April 6, 1912. Serial No. 688,852.

To all whom it may concern:

Be it known that I, JESSE BROWN WALKER, a citizen of the United States, and a resident of Savannah, in the county of Hardin and State of Tennessee, have invented certain new and useful Improvements in Internal-Combustion Engines, of which the following is a specification.

My present invention relates to internal combustion engines, and more particularly to those of the four-cycle type, my general object being to produce a structure by which increased power may be obtained, and which will, at the same time entail but minimum change or departure from the usual construction.

Specifically my improvements consist in providing an enlarged explosion chamber with which one end of the piston cylinder communicates, and with which the usual intake and exhaust ports have valved communication, and in the further provision of a supplementary intake part having valved communication with the crank case and a 25 valved by-pass communicating between the crank case and the piston cylinder, the mouth of which is uncovered by the piston at one end of the stroke of the latter. Through the intended operation of these parts, I attain the above object and accomplish certain advantages as will be hereinafter described in connection with the accompanying drawing, in which the figure is a central vertical section through an engine constructed in accordance with my invention.

Referring now to this drawing, the crank case A supports the usual power shaft B, to the crank b of which is connected the inner end of the pitman C, the outer end of which is connected to the cross pin d of the piston D. The power shaft B also carries a gear wheel b' which is in mesh with an enlarged gear wheel e, the latter being secured upon a shaft E extending also into the crank case and provided therein with a cam e' for a purpose which will be hereinafter particularly referred to.

The casing F of the engine, which is superposed upon the crank case A, is provided with a piston cylinder f in which the piston D travels and which opens at its lower end into the crank case A. The cylinder f is further provided with an upper enlarged explosion chamber f' into which the upper end of the piston cylinder opens and with which the intake and exhaust ports G and

H respectively communicate, through their valves g and h. These valves open inwardly into the explosion chamber f' as shown, and the intake valve g is normally held closed by means of its spring g' which permits the same to open when a vacuum is produced in the explosion chamber by the downward inward stroke of the piston D preceding each explosion stroke. The exhaust valve h is held closed by its spring h' at all times except when the cam e' engages the roller h² at the lower end of the elongated valve rod h², the action of which is to open valve h against the tension of spring h'.

The intake port G and the exhaust port H are diametrically opposed. Below the intake port G the casing F is provided with a supplemental intake port I which communicates with the crank case A through an additional and inwardly opening valve i normally held by its spring i'. Diametrically opposite to the supplemental intake port I, the casing F is provided with a by-pass J, the lower end of which opens into the crank case, and the upper end of which communicates with the piston cylinder f at a point slightly above the upper end of the piston D when the latter is at the end of its inward or downward stroke. The by-pass J is provided with a valve j which is normally held closed by means of its spring j', and which controls communication between the crank case and the piston cylinder.

The explosion is produced through the usual spark plug K which is let into the top of the casing F at a point substantially central of the explosion chamber f' and the respective end of the piston cylinder f. When an explosion takes place, the piston D moves inwardly and downwardly under the effect thereof, and during this cycle of the operation, the intake valve g and the by-pass valve j are held closed by means of the pressure in the explosion chamber and engine cylinder incident to the explosion. Upon the outward movement of the piston D corresponding to the second cycle of its operation, and the moment the mouth of the by-pass J is closed thereby, the exhaust valve h is opened through the mechanical connections previously described, so that the pressure in the explosion chamber and engine cylinder is at once relieved and the burnt gases forced outwardly through the exhaust port during the succeeding move-

ment of the piston in the same cycle. During this movement of the piston, a partial vacuum is created in the crank case A which acts to suck into the crank case a supply of fresh gas through the supplemental intake 1 and its valve *i*.

During the third cycle or downward movement of the piston D, a fresh charge of gas at atmospheric pressure is sucked into the explosion chamber through the inlet valve *g*, and when the piston reaches its lowest point of travel during this cycle, the explosion chamber is filled with fresh gas, or at least filled to an extent possible to fill 10 the same by the suction created by the downward movement of the piston. As before mentioned, however, I have enlarged the explosion chamber to a considerable extent, for the purpose of obtaining increased 15 power at each explosion, without materially increasing the size or weight of the engine as a whole, and to further this end, the downward movement of the piston upon its third cycle uncovers the mouth of the by-pass J, and inasmuch as the explosion chamber at this time is filled with fresh gas which is at atmospheric pressure only, the pressure within the crank case, occasioned 20 by two suctions through the valve *i*, is sufficient to force valve *j* open and pump an additional charge, under pressure, into the explosion chamber. Thus, when the piston ascends upon its fourth cycle of movement, 25 the enlarged explosion chamber is filled not only with a supply of gas sucked in at atmospheric pressure, but also with a supply of gas pumped therein and under pressure. The result is that an explosion takes place having considerably greater power over the 30 ordinary engine, by virtue of the increased number of energy producing units, this explosion being effected by the plug K when the upper end of the piston D has reached a point substantially level with the upper 35 end of the piston cylinder *f*.

It will be apparent from the foregoing

that I obtain a mixture in the explosion chamber which comprises gas at atmospheric pressure and compressed, and I have found that this mixture, together with an 50 enlarged explosion chamber, is productive of better results and greater power than is produced in the usual four-cycle engine. I have also found that by the joint action of the parts a more even and uniform suction 55 on the carburetor is effected, which in turn produces a better and more uniform charge, more especially where the charge is either more rich or poor than normal.

I claim:—

In a four cycle engine, the combination with a casing having a piston cylinder, a shallow annularly enlarged explosion chamber at one end of the piston cylinder, provided with a valved fuel intake port at one 60 side and a valved exhaust port at the opposite side, the valves of both of which ports open into the explosion chamber, mechanical connections for opening the valve of the exhaust port, a piston in the cylinder, 70 a closed crank case at the opposite end of the cylinder having a valved fuel intake port, said casing also having a valved by-pass communicating between the crank case and the piston cylinder at a point in the 75 latter adjacent the inner limit of movement of the piston, and means for exploding the charge in the explosion chamber, said crank case intake port and said by-pass being formed in the casing along the piston cylinder upon diametrically opposite sides thereof, and the valves thereof opening inwardly whereby said valves together with the valves of the explosion chamber intake 80 may be controlled by springs alone to operate automatically in supplying the desired charge to the piston cylinder.

JESSE BROWN WALKER.
